 Maplewood, N.J. 07040
 Filed July 8, 1966, Ser. No. 563,883
 2 Claims. (Cl. 30—358)

ABSTRACT OF THE DISCLOSURE

A punch has a first jaw carrying a punching pin that is coactive with a die opening in a flat face of a second jaw, and a gauge formed of sheet metal has a main flat portion set on said flat face of the second jaw and formed with a gauge edge extending upwardly from said flat face in transverse relation to the second jaw, said main portion also having an arm formed with a gauging edge in angular relation to the first-mentioned gauging edge so that said edges are adapted to be abutted by two meeting edges of a card to be punched and the first-mentioned edge has a notch to provide clearance for said punching pin.

This invention relates in general to a punch for indexing cards, for example, photograph slides which comprise transparencies mounted in cardboard frames; and a primary object of the invention is to provide an attachment for a punch, particularly a hand punch, whereby a card like a photograph slide may be accurately positioned with each of two angularly related sides in a predetermined relation to the punching elements such as a punch pin and a cooperative die.

The invention is especially useful for producing a notch in an edge of a slide in a predetermined relation to an angularly related edge of the slide so that the slide may be easily and accurately oriented in a slide projector, the notch and its relation to the second-mentioned edge of the slide indicating by sight or touch the proper positioning of a slide in a projector.

Another object of the invention is to provide a novel and improved construction and combination of a hand punch and a gauge by which the proper positioning of the card or slide holder relative to the punch can be easily and quickly effected.

A further object is to provide a novel and improved gauge attachment that can be easily applied to and removed from a punch and which shall be simple and inexpensive in construction.

Other objects, advantages and results of the invention will be brought out by the following description in conjunction with the following drawings in which:

FIGURE 1 is a side elevation of one type of punch and a gauge attachment therefor according to one embodiment of the invention;

FIGURE 2 is an enlarged fragmentary central longitudinal sectional view through the jaws, the punching elements and the gauge attachment;

FIGURE 3 is a fragmentary horizontal sectional view approximately on the plane of line 3—3 of FIGURE 2;

FIGURE 4 is a fragmentary side elevation of the side of the punch jaws and the gauge attachment opposite that shown in FIGURE 1;

FIGURE 5 is a perspective view of a photograph slide that has been notched or indexed by the punch, and

FIGURE 6 is an enlarged perspective view of the gauge attachment.

For the purpose of illustrating the principles of the invention, I have shown in the drawings a known type of hand punch which includes a body portion A having a hand grip 1 extending therefrom, the body portion being formed to provide the jaws 2 and 3 which are separated by a slot 4 into which is inserted the card, sheet or photo-

2

graph slide to be punched. The jaws 2 and 3, respectively, carry the punching elements, that is the punching pin 5 and the die 6. The punching pin is actuated by lever 7 having the grip portion 8 and pivotally secured to the body portion by the pivot pin 9. The lever 7 is associated with the punching pin 5 so as to actuate the pin and cause it to be brought into cooperative relation with the die 6, to punch the card. An expansion spring 10 is arranged between the grip portions 1 and 8 so that the grip portions will be urged normally into an extended position with the punching pin in spaced relation to the die as best shown in FIGURES 1 and 2. Obviously, the punch pin may have other shapes than cylindrical as shown.

The jaw 3 has a plate portion 11 formed with a flat face flush with the edges of the opening 6a through the die 6, and the jaw 4 has a plate portion 12 formed with a flat face in opposed relation to the face of the plate 11 and through an opening in which reciprocates the punching pin 5. The faces of the plate portions 11 and 12 of the jaw are spaced apart a distance slightly greater than thickness of the card or photograph slide to be punched, and in accordance with the invention a gauge B is interposed between the plate portions 11 and 12 of the jaws.

The gauge is shown as comprising a piece of sheet metal having a flat main portion 13 to lie flatwise upon the face of the plate portion 11 of the jaw 3 and formed with opposed parallel flanges 14 one to abuttingly engage each of opposite sides of the jaw 3. In other words, the flanges 14 are spaced apart a distance approximately equal to the width of the jaw 3. The gauge is separably secured to the jaw in any suitable manner, preferably by screws 15 that pass through openings 16 in the flanges 14 and are screwed into complementarily threaded holes in the jaw. The gauge has one gauging edge 17 that is disposed transversely of the jaw 3 and in chordal or transverse relation to the opening 6a of the die as best shown in FIGURE 3, and said edge has a notch 18 therein that is preferably arcuate and approximately concentric with the die opening 6a. However, the notch may be of different shape and size, its primary purpose being to provide clearance for the punching pin. The gauging edge 17 is adapted to be abutted by one edge 19 of a photograph slide C that is to be notched, and the gauge has another gauging edge 20 to be abutted by an edge 21 of the photograph slide that is angularly related to the side 19 in the present instance at a 90° angle, these gauging edges serve to locate the slide edges 19 and 20 in proper relation to the die opening. The gauging edge 20 is formed on a lateral and forwardly extending arm 21 of the main portion 13 with said edge 20 in the present instance spaced from the corresponding side of the jaw 3 and disposed approximately parallel thereto.

With this construction, when it is desired to notch a photograph slide, the slide is viewed by the operator and the two angularly related edges that are to be used for orienting the slide in a projector are determined, after which the slide is inserted in the slot 4 between the jaws 2 and 3 with one edge, in the present instance the edge 19 abutting the gauging edge 17 of the gauge and with the other edge of the slide, in the present instance the edge 21 abutting the gauging edge 20, whereupon the grip portions 1 and 8 of the punch are squeezed in the usual way to force the punching pin 5 into cutting relation to the die, as a result of which a notch 23 is formed in the edge of the slide that overlies the die opening.

It will be understood by those skilled in the art that the gauge may be adjustably mounted on the jaw 3 and the depth of the notch 23 in the slide can be varied by changing the chordal relation of the gauging edge 17 to the die opening, and similarly the position of the notch with respect to the edge 21 may be varied by changing the distance of the gauging edge 20 from the die opening.

Other modifications and changes in the structural details of the punch and the gauge may be made within the spirit and scope of the invention as defined in the appended claims.

I claim:

1. A card indexing punch comprising a first jaw having a punching pin mounted therein and a second jaw having a plate portion provided with a flat face which forms between itself and the first jaw a slot open at one end to receive a polyedged card to be punched, said second jaw also having a die opening extending through said flat face cooperative with said punching pin, means for actuating said pin into and out of coactive relation to said die opening, and a gauge formed of sheet material having a flat main portion set on said flat face of the second jaw, one edge of said main portion extending transversely of the second jaw and extending upwardly from said flat face providing a gauging edge at the side of said die opening opposite said open end of the slot between said jaws, said main portion also having an arm in the plane of said flat main portion and extending toward said open end of said slot between the jaws and formed with an edge in angular relation to the first-mentioned edge, said flat face of the second jaw providing a support for said card to be punched and said gauging edges being adapted to be abutted by two meeting edges of said card, and the first-mentioned gauging edge having a notch to provide clearance for said punching pin.

2. For use with the jaw of a punch which has a die opening cooperative with a punching pin, a gauge formed of a single piece of sheet material with a flat main portion to set on said jaw and having parallel flanges at two opposite edges angularly related to said main portion to abut opposite sides of the jaw, said main portion having one of its edges constituting a gauging edge extending perpendicularly to the planes of said flanges, said main portion also having a lateral arm in the same plane with said main portion and extending beyond said first-mentioned edge and one of whose edges is a gauging edge angularly related to the first-mentioned gauging edge, said first-mentioned gauging edge having a notch to provide clearance for a punching pin coacting with said die opening.
